UNITED STATES PATENT OFFICE

2,690,311

WINDING SPOOL

Charles K. Dunlap, Hartsville, S. C., assignor to
 Sonoco Products Company, a corporation of
 South Carolina

Application March 27, 1951, Serial No. 217,745

2 Claims. (Cl. 242—119)

1

This invention relates to an improved construction for winding spools of the type having a barrel for supporting yarn windings, or the like, and flange-like head members mounted on each end of the barrel for retaining the windings thereon; and to a unique method for forming spools of this sort.

Such spools or carriers having a central barrel fitted with retaining flanges at each end are widely used in the textile industry and require an inexpensive construction that is sturdy enough to withstand rough usage in order to be structurally and economically satisfactory.

In accordance with the present invention, there is now provided a winding spool formed entirely of paper or fibrous elements that lends itself well to large-scale, low-cost manufacture, and that is exceptionally strong and serviceable. A particular feature of the winding spool of the present invention is the manner in which the flange heads are secured in assembled relation on the spool barrel.

The present invention is described in detail below in connection with the accompanying drawings, in which:

Fig. 1 is a side elevation, partly in section, showing a winding spool embodying the present invention;

Fig. 2 is a transverse section taken substantially on the line 2—2 in Fig. 1; and

Fig. 3 is a fragmentary exploded view, partly in section, illustrating the method by which the head members are secured on the ends of the spool body.

Referring now in detail to the drawing, and more particularly at first to Fig. 1, the winding spool of the present invention, as indicated generally by the reference numeral 4, comprises a tubular paper body 6 that may be formed by convolutely or spirally winding a paper sheet in the conventional manner to form a multi-ply spool barrel of any desired wall thickness. If desired, the outer surface of this barrel 6 may be treated readily with resinous hardening agents and sized, as disclosed in copending application Serial No. 151,013, filed March 21, 1950, for example, to impart a relatively hard finish, free of unevenness or irregularities. After the barrel 6 is formed in this manner, it is further swaged at its ends according to the present invention, as indicated at 8 in Fig. 3, in preparation for assembly with flange heads 10 as will be explained in further detail presently.

The head members 10 for the spool 4 are preferably molded of fibrous material and may be

2

formed suitably, for example, in accordance with the disclosure of copending application Serial No. 738,052, filed March 29, 1947, so that they are rendered tough and strong by resin impregnation.

These head members 10 will in the usual case be circular in form as shown in the drawing, and are particularly characterized by a central opening or perforation 12 having a serrated inner peripheral edge as shown at 14 in Fig. 2. The diameter of this central opening 12 as measured to the bases of the serrations 14 is substantially the same as the outside diameter of spool barrel 6.

In assembling the flange heads 10 on the spool barrel 6, the swaged down ends 8 of the barrel 6 are first disposed through the openings 12 of the head members 10, and the ends 8 are then forced outwardly as shown at 14 in Fig. 1 so that the serrations 14 at the openings 12 bite into and thereby become imbedded in and securely locked to barrel 6 with the barrel portion 14 tapered or flared outwardly to maintain this relation. Both the inward swaging to form the barrel ends 8 and the outward forming to provide the flared barrel portions 14 may be accomplished in a usual type of forming die, either one that is stationary or one that is rotated to obtain a spinning effect. Also, the flared barrel portions 14 may be given a special resin treatment and then hardened to set them in place, and a treatment of this sort may be carried out by using a heated forming die, after dipping the swaged down ends 8 of the barrel 6 in a suitable treating resin, such as a phenol-formaldehyde resin, to form the outwardly flared barrel portions 14.

If desired, the spool 4 may be further fitted with end bushings 16 having bores as at 18 to receive spindles for mounting the spool 4 during subsequent use. If such end bushings 16 are used, they should also be flared outwardly to fit the flared barrel portions 14 and thereby further support the spool elements in assembled relation.

The present invention has been described in detail above for purposes of illustration only and is not intended to be limited by this description or otherwise except as defined in the appended claims.

I claim:

1. A winding spool comprising a multi-ply, tubular, paper barrel and centrally perforated, relatively hard, flange heads mounted coaxially thereon adjacent the ends thereof, said barrel being of uniform diameter between said flange heads, and said flange heads being secured to

said barrel by means of a plurality of protuberances projecting radially inwardly from the inner periphery of the central perforation in said flange heads and substantially completely imbedded in the surface of said barrel by reason of an outward flaring of the end portions of said barrel beyond said flange heads.

2. A winding spool comprising a tubular barrel of deformable paper material and a pair of centrally perforated, relatively hard, flange head members mounted coaxially thereon adjacent the ends of said barrel, said barrel being of uniform diameter between and through said head members, the central perforations in said head members being cylindrical in form with radially projecting serrations disposed along the peripheral edge of said central perforations and imbedded in the surface of said barrel to secure said heads thereon, the diameter of said central perforations corresponding substantially at the base of said serrations with the diameter of said barrel between said head members, and said bar-

rel being flared outwardly at each end beyond said head members.
